UNITED STATES PATENT OFFICE

143,009

DESIGN FOR A CASTING MACHINE

Robert J. Lindsey, Mount Gilead, Ohio, assignor
to The Hydraulic Development Corporation,
Inc., Mount Gilead, Ohio, a corporation of Del-
aware

Application September 4, 1944, Serial No. 115,187

Term of patent 7 years

(Cl. D55—1)

To all whom it may concern:

Be it known that I, Robert J. Lindsey, a resident of Mount Gilead, in the county of Morrow and State of Ohio, have invented a new, original, and ornamental Design for a Casting Machine, of which the following is a specification, reference being had to the accompanying drawing, forming part thereof wherein:

Figure 1 is a side elevational view of the casting machine showing my new design;

Figure 2 is a side elevational view of the casting machine as viewed from the opposite side thereof with respect to Figure 1;

Figure 3 is an end elevational view of the casting machine as appearing from the right-hand end thereof with regard to Figure 1.

Figure 4 is an end elevational view of the casting machine as appearing from the left-hand end of the machine with regard to Figure 1;

Figure 5 is a top plan view of the casting machine.

I claim:

The ornamental design for a casting machine, substantially as shown.

ROBERT J. LINDSEY.
